UNITED STATES PATENT OFFICE.

RAYMOND K. GRAY, OF CHICAGO, ILLINOIS, ASSIGNOR TO THE GRAYNIE CORPORATION, OF CHICAGO, ILLINOIS, A CORPORATION OF ILLINOIS.

LOCKING DEVICE.

1,386,778.

Specification of Letters Patent. Patented Aug. 9, 1921.

Application filed October 29, 1920. Serial No. 420,344.

To all whom it may concern:

Be it known that I, RAYMOND K. GRAY, a citizen of the United States, and a resident of Chicago, in the county of Cook and State 5 of Illinois, have invented certain new and useful Improvements in Locking Devices, of which the following is a specification.

This invention relates to locking devices, and more particularly to those of the chain 10 and padlock type adapted for various uses, among which may be mentioned the locking of spare tires and rims to the body of motor vehicles to prevent the theft or unauthorized removal thereof. 15 A locking device of the character described preferably consists of a stout chain having the padlock or lock proper fixed to one end, the opposite or free end being connected and locked to the padlock after the 20 chain is passed through or about the parts to be locked together.

The object of the invention is to provide a simple, yet strong and dependable lock, capable of resisting breakage or tampering 25 with by persons bent on unlocking the device for the purpose of stealing the articles locked thereby. The novel features of the device are hereinafter fully described and illustrated in the accompanying drawings, 30 in which—

Figure 1 is a view in side elevation of the locking device, with parts in locked position,

Fig. 2 is a view in side elevation of the device showing the parts in unlocked position, 35 with a portion of the casing broken away,

Fig. 3 is a cross-sectional view taken on line 3—3 of Fig. 1, and

Fig. 4 is a view in perspective of the locking bolt and arm removed.

40 The locking device comprises in general a body or lock casing 1, a block 2, and a link chain 3 permanently connected at one end to the casing 1, and to have its free end connected and disconnected from the lock proper by the locking and unlocking of the latter. As a preferable arrangement, the casing 1 and block 2 are separable, the latter 45 including suitable locking mechanism operative by means of a key.

50 The lock casing 1 consists of a metal shell of rectangular shape having its exterior surfaces slightly rounded or convex to afford a shape conveniently handled and pleasing in

appearance. The casing is elongated to a small degree, the interior space or cavity 55 being of corresponding proportions and having a full entrance opening in one end through which the block 2 is inserted. The opposite or lower end of the casing is closed and a U-shaped link 4 is securely anchored 60 therein, to which the links of the chain 3 are fastened.

The block 2, as its name suggests, is a solid rectangular block of metal proportioned as to length, width and thickness to fit within 65 and to slide into and out of the cavity of the casing 1. The upper end of the block is provided with a marginal flange 2^a adapted to engage flatwise against the open end of the casing, and to close the same when the 70 parts are in locked position. The locking mechanism carried by the block comprises a barrel or cylindric plug 5 rotatively mounted in an annular bore extending transversely through the block at a point near the inner 75 end and somewhat offset from the central axis thereof. The barrel or plug 5, which need not be described and illustrated in detail, is of the usual construction employed in locks of the cylinder type, the same being 80 operative only when the proper key is inserted in the key slot 5^a disposed in slightly eccentric relation to the axis of rotation of the plug 5, and located at one end thereof. As a 85 preferable arrangement, the locking mechanism is constructed so that the key can only be inserted and removed from the slot when the parts are in unlocked position. Pivottally connected to the barrel 5 at the opposite end from the key slot 5^a is a crank arm 6 engag-

ing a pin 7 carried by the barrel and set off center or eccentrically to the axis of rotation thereof. The crank arm extends laterally from the barrel toward the side wall of the casing distant from the barrel, and is connected at its outer end by a simple form of tongue and groove connection with a bolt or locking block 8, slidably mounted in a transverse slot 9 formed in the face of the block 2. The side wall of the casing, adjacent to the 100 bolt 8, is concave to conform to the contour of the outer surface of the casing, is provided intermediate the length thereof with an inwardly projecting shoulder 10 in transverse alignment with said bolt. In the wall of the 105 casing 1, and located in registering relation

with the key slot 5^a of the barrel 5 when the block is in locking position, is a circular aperture 11 thereby permitting a key to be inserted into the locking mechanism, this 5 aperture being of sufficient diameter to permit the slightly eccentric rotation of the barrel 5 in turning the key. Communicating with the aperture 11 at its upper edge is a narrow slot 12 extending longitudinally of 10 the casing toward the open end thereof, said slot being slightly offset from the center of said aperture. The purpose of this slot will be presently pointed out.

The locking mechanism is operated as before suggested, by inserting the proper key 15 into the key slot through the aperture 11 in the wall of the casing 1. The key slot 5^a in unlocking position, extends vertically, so by rotating the barrel in a counter-clockwise 20 direction through a quarter turn, the latch is thrown outwardly and into locking engagement with the shoulder 10 to the position shown in Fig. 1. In like manner the bolt is drawn back by rotating the barrel in the opposite direction, whereupon the block 2 may 25 be withdrawn from the casing, as shown in Fig. 2. It is to be observed that in locking position the key slot, and hence the key, are positioned vertically or in alinement with 30 the narrow slot 12 in the wall of the casing; thus the block may be withdrawn without removing the key from the lock; that is, the block is only partially withdrawn, the key passing along the slot 12 until it strikes the 35 end thereof, and preventing further removal of the block. As it will be presently pointed out, it is not necessary to entirely withdraw the block to accomplish the locking or 40 unlocking operations; therefore it is manifestly more desirable that the key remain within the key slot during consecutive acts of unlocking and locking the device.

As a means of connecting the free end of the chain 3 to the padlock, the following is 45 employed: In the opposite walls and extending longitudinally from the open end of the casing are provided two slots 13—13, and in the block 2 is a single slot 14 extending at right angles to the slots 13—13, and 50 transversely to one of the longitudinal edges of the block, said slots 13 and 14 being so arranged that when the parts are in locked position, the inner ends of said slots are in 55 registering relation, thereby forming a circular opening extending through the casing. Thus, if the link 15 be considered the free end of the chain 3, it would be inserted in the slot 14 of the block when the same is partially withdrawn from the casing, and then the 60 block forced into the casing and locked, the link is secured within the co-acting slots 13 and 14.

The construction herein illustrated and described provides a substantial and reliable locking device, particularly well adapted for

the purposes for which it is designed, in that the locking mechanism is completely inclosed and protected by the outer casing, not only affording resistance to efforts to break or pry open the lock, but protection 70 against the entrance of mud and dirt into the more delicate parts, the latter feature being particularly desirable in a locking device constantly exposed to the elements and road conditions. In short, the several novel 75 features, singly and in combination, co-operate to provide the desirable form of locking device hereinbefore described, and more specifically set forth in the appended claims.

I claim as my invention:

1. A locking device comprising a lock casing, a block insertible in said casing, key operated locking mechanism carried by said block and operative through an opening in said casing registering with said locking 85 mechanism when said block is in locking position, and means permitting the withdrawal of said block when a key is in the locking mechanism.

2. A locking device comprising a lock casing, a block insertible in said casing, locking mechanism carried by said block, and comprising a key operated cylindric locking member, an opening formed in said casing and adapted to register with said cylindric 95 locking member when said block is in locking position, and means permitting the withdrawal of said block from locking position without removal of the key from the cylindric locking member.

3. A locking device comprising a lock casing, a block insertible in said casing, locking mechanism carried by said block comprising a key operated member, a locking bolt operatively connected with said key operated member, and adapted to be moved thereby into and out of locking engagement with a shoulder formed integral with said casing, the latter being provided with an opening in registering relation with said key operated member, and a slot permitting the relative movement of said block and casing when a key is in said key operated member.

4. A locking device comprising a lock casing, a block insertible into an opening in said casing, locking mechanism carried by said block, comprising a key actuated member, said casing being provided with an aperture positioned to register with said key actuated member when said block is in locking position, and a slot communicating with said aperture permitting the withdrawal of said block into unlocking position.

5. A locking device comprising a lock casing, a locking block insertible in said casing, and provided with a slot adapted to be open at one end when said block is partly withdrawn from said casing, and to be closed when said block is in locking position.

tion, key operated locking mechanism carried by said block, and a key slot formed in said casing and acting to permit the withdrawal of said block when a key is within 5 the locking mechanism.

6. A locking device comprising a lock casing, a locking block insertible in said casing, a slot formed in said block and open at one end when said block is withdrawn from the 10 casing, and a coöperating slot in said casing adapted to close the first mentioned slot when said block is advanced into locking position.

7. A locking device comprising a lock casing, a block insertible in said casing, locking mechanism for locking said block in 15 said casing, a slot formed in one edge of said block and open at its outer end when said block is in partially withdrawn position, and a transverse slot in said casing 20 registering with the inner end of the slot in

said block, and closing the open end thereof when said block is in locking position.

8. A locking device comprising a lock casing having a cavity open at one end, a block 5 insertible in said cavity and provided with a marginal flange serving as a closure therefor, locking mechanism carried by said block, an open slot formed in said block and adapted to receive a link of a chain when 10 said block is in unlocked position, a transverse slot in said casing coöperating with the slot of said block to secure said link when said block is in locking position, and means permitting the withdrawal of said 30 block into unlocking position with a key inserted in said locking mechanism.

In witness whereof, I hereunto subscribe my name this 26th day of October, A. D. 1920.

RAYMOND K. GRAY.
